UNITED STATES PATENT OFFICE.

LUIGI ANGELINI, OF ROME, ITALY.

CARBURETOR.

Application filed March 11, 1924, Serial No. 698,559, and in Italy March 16, 1923.

This invention relates to carburetors for internal combustion engines in which one or more nozzles is or are used, and with or without a pilot nozzle.

It is known in connection with single nozzle carburetors to provide a Venturi nozzle chamber which is surrounded by an annular space in communication with an automatically acting extra air supply valve, the extra air being admitted within the Venturi chamber by a system of perforations and thus forming the necessary mixture with the fuel.

It has also been proposed in a carburetor having a Venturi chamber within which the nozzle is arranged, to provide an annular space around the chamber, to which extra air may be admitted through an automatically acting air valve. The air supplied in this way is led into the mixing chamber at the end of the Venturi chamber through an annular opening, where it is deflected inwards by a conical baffle which effects a mixture of the air and fuel and causes eddies so as to facilitate the intimate mixture of the fluids.

The invention consists in an improved carburetor in which the air supply for the jet is capable of being controlled by one of two alternative devices according to the engine revolution speed, wherein for low speed the air is controlled by being passed through a primary calibrated opening immediately adjacent the jet, and at a higher engine revolution speed a correspondingly greater supply of air is automatically admitted and controlled by a second and larger calibrated opening, the primary calibrated opening then functioning merely as an inlet.

The invention will now be described with reference to the accompanying drawings in which:

Fig. 1 is a vertical cross section of a vertical carburetor according to the invention.

Figs. 2 and 3 show a horizontal carburetor,

Fig. 2 being a horizontal cross section taken on line 2—2 of Fig. 3, and

Fig. 3 a vertical section taken on line 3—3 of Fig. 2.

Referring to Fig. 1, the carbureted mixture passes to the engine by way of the induction pipe 1, from the two chambers 2 and 3. The carburetor is connected to the engine by flange 4. 5 and 6 are independent throttle valves, one for each of the chambers

2 and 3, while 7 and 8 are the respective nozzles in the chambers. 9 is the air admission opening for both chambers. The chambers are provided with a heating fluid chamber 12 through which may be circulated, by means of the inlet 10 and the outlet 11, hot water or the exhaust products of combustion. The lower end of each chamber 2 and 3, is fitted with a Venturi tube 13, 14 respectively; and of these the tube 13 with its choke or air passage I is of ordinary construction, whilst the tube 14 is of special construction, according to which it is transversely divided as shown in order to provide two spaced choke or air passages H and X respectively, which are both carefully calibrated. The passage H is circular and has centrally arranged therein the nozzle 8 which reduces its total area, and is adapted to afford passage to a quantity of air correctly proportioned to the quantity of petrol discharged by the nozzle 8 at low engine revolution speed, while, when the engine is running at high engine revolution speed, the passage X of full circular area, is brought into action to supply to larger quantity of air. For this purpose, an air valve 15 is provided which is under the control of a very light coil spring 15', the valve chamber being in communication by passage 16 with an annular chamber 21 that surrounds the spaced portions of the choke passages X and H. The valve 15 is designed to open and admit air with a predetermined increase of engine revolution speed, thus admitting the necessary quantity of air. It is to be noted that at low speed, the volume of air passing through the Venturi tube 14 will be controlled by the calibrated passage H, but on an increase of speed, the function of air control will be transferred to the calibrated passage X, and then the passage H will function merely as an air inlet. In order to afford a braking action on the engine when desired, the carburetor is fitted towards its upper end, with a conical valve 17 for the admission of additional air.

Referring to Figures 2 and 3, a horizontal carburetor is shown, in which similar reference letters indicate like parts. In this case the two carburetor chambers 2 and 3 are reduced to a minimum and converge towards a port or passage formed in a rotary throttling plug 19 by which the engine revolution speed may be controlled. The nozzles 7 and 8 are transversely arranged

within the two Venturi tubes 13 and 14, and instead of the larger passage X being of conical form, it is cylindrical and in communication by means of duct 16 with the air admitted through valve 15. Branching from the duct 16 is an air passageway 24, the end of which is designed to be covered or uncovered by the rotary plug 19 so as to come into action during the last few millimeters of opening of the Venturi nozzle chamber 13.

A pilot nozzle for slow running of known type is provided and so positioned that the passage for the fuel mixture to the induction pipe is cut off on opening the mixture throttle valve in the known manner.

The said device comprises a hollow body 25 screwed into the carburetor and has a transverse port 27 about midway of its length that connects its bore with an outer concentric annular chamber 28. Such chamber is in communication with a duct 29 in the casing of the throttle plug valve 19. The latter is provided with a duct 36 opening into the plug. The inner end of the duct 36 is adapted to register with the duct 29 when the valve is so turned that both of the Venturi tubes are closed, but its outer end, as shown in Fig. 3, is directed downwards so that it opens into the internal space of the plug by means of a small orifice 19^b in the wall of plug 19 that communicates with the intake 1 when the plug 19 is closed, so that the engine will run light.

The lower end of the body 25 registers co-axially with the nozzle 30 so that the fuel discharged therefrom mixes with air in the bore of the body 25 and passing successively through port 27, annular chamber 28, duct 29 and the duct 36, and is admitted to the induction pipe. By moving the body 25 more or less towards the nozzle 30 placed beneath it, a more or less rich mixture is formed.

In order to control the number of revolutions of the engine, there is provided on the top of body 25 an adjustable screw 31 which by being screwed in, forms a partial closure of the port 27 up to such a point as to give passage to only a very small quantity of mixture whereby the engine is reduced to very slow running.

From what has been stated above, it will be understood that when the throttle plug valve 19 is opened for effective normal running of the engine under load, the duct 29 will no longer be in register with the duct 36, so that the above described slow running jet is put completely out of action.

The operation of the carburetor is as follows:

Assuming that the throttle valve 6 is open and that the engine is running at slow speed, the carburetor chamber 2 is brought into action. The suction of the engine will now

cause a flow of air through the annular calibrated choke passage H drawing sufficient fuel through the nozzle 8 to make a correct mixture. Should the engine speed increase then the mixture will be found too rich as the calibrated passage H cannot pass sufficient air. Owing to the tension then brought about in the chamber 2, the valve 15 opens automatically and admits an auxiliary supply of air to the annular chamber 21 surrounding the Venturi chamber 14, such extra air flowing through the calibrated choke passage X of larger area than that of H whereby a correct mixture for the higher engine speed is obtained. Thus the function of air control is transferred from the annular passage H to the larger opening X and maintains the right mixture.

It is to be understood that should still higher engine speed be required, then the extra carburetor chamber 2 may be brought into action if such is needed. Thus the carburetor may be used with only the single chamber 2 with or without a pilot nozzle, or it may be supplemented by the chamber 3.

In Figure 1 showing the vertical carburetor, the throttle passage H and X are combined in one block inserted into the carburetor body, the said block having lateral holes so that the interior (and consequently passage X) may communicate with chamber 21 and thereupon with valve 15 through passage 16.

In Figures 2 and 3 showing a horizontal carburetor, owing to the different arrangement of the members comprising the carburetor, the throttle passages H and X are not combined into a single block but H is fitted separately. They also could be made by boring suitable holes in the carburetor body.

Working is identical, in both types, there being throttle passages H with the fuel nozzle in the center in both. The passage X is provided, which in both types communicates in the same manner with atmosphere through and by chamber 21, passage 16 and valve 15.

Passage 24, Fig. 2, comes into operation when the mixture throttle valve is fully open and mixture is being supplied through Venturi nozzle chamber 13. Passage 24 is for the purpose of maintaining the suction on the valve 15 so that it remains open, and therefore the working of the carburetor constant.

Having now particularly described my said invention, what I claim is:

In a carburetor, in combination, a body having an induction tube therein and two air inlets at an angle to each other and to said tube, a rotatable member having a passage therethrough adapted to connect one or both inlets to said tube, a choke in each inlet, a fuel nozzle in each choke, a second choke

of larger area than the first between one member being adapted to close said last mentioned passage when the single air inlet having two chokes is in use and to open the 10 same when both air inlets are in use.
5 space and having an automatic air valve In testimony whereof I have hereunto opening therein, a passage leading from said signed my name.
chamber to the induction tube, said mem- LUIGI ANGELINI.
